UNITED STATES PATENT OFFICE.

ZERAH G. HAYDEN, OF ELDORA, IOWA.

LADDER.

1,250,311.

Specification of Letters Patent. Patented Dec. 18, 1917.

Application filed February 3, 1917. Serial No. 146,405

To all whom it may concern:

Be it known that I, ZERAH G. HAYDEN, a citizen of the United States, residing at Eldora, in the county of Hardin and State 5 of Iowa, have invented certain new and useful Improvements in Ladders; and I do hereby declare the following to be a full, clear, and exact description of the invention, such as will enable others skilled in the art 10 to which it appertains to make and use the same.

The primary object of this invention is the provision of a novel form of ladder designed to be associated with a standard, in the nature of a post or pole or mast, or with a building structure, so as to admit of the ascent of a person to the top of a standard or structure being effected in a convenient, safe and expeditious manner; also to admit of the descent of the person from the top of the pole being effected in a similar manner.

Another object of the invention is the provision of a device of this character that will be of simple and durable construction, can be readily mounted in operative position, and which includes a series of steps or rungs which can be conveniently adjusted so as to be set at various distances apart.

30 Other objects will appear and be better understood from that embodiment of my invention of which the following is a specification, reference being had to the accompanying drawings forming a part thereof, in
35 which:

Figure 1 is a side elevation of a fence structure, showing a fence post equipped with a ladder constructed in accordance with my invention.

40 Fig. 2 is a detail perspective view of the upper end of one of the ladder sections, showing the same detached from operative position, and showing the manner of connecting one of the steps or rungs thereto,

45 Fig. 3 is a section taken on the line 3—3 of Fig. 1,

Fig. 4 is a perspective view of a modified form of step or rung, and

Fig. 5 is a detail perspective view of another modified form of step or rung.

Referring to the drawings in detail, the letter A designates a fence structure and B a fence post. Associated with the post B is a ladder formed of a pair of sections mounted, respectively, on opposite sides of the post, as shown in Fig. 1. Each section includes

a standard 1, which engages along the adjacent side of the post and has its upper end bent to provide a flange 2, which overlies the upper end of the post and is secured thereto in any suitable manner. Each standard 1 is provided at spaced points throughout its length with outwardly offset portions 3, and each offset portion 3 has stamped therefrom a pair of inwardly extending tongues 4, which are of L-shape in configuration. Mounted on each of the standards 1 is a plurality of steps, or rungs, designated 5. Each of the steps or rungs 5 is of L-shape, having a vertical portion 6 and a horizontal portion 7. The horizontal portion 7 of each step or rung 5 is provided, adjacent the point of juncture between the vertical portion 6 and the horizontal portion 7, with a slot 8 for the passage of the adjacent standard 1, and the vertical portions 6 of the steps or rungs 5 lie, as shown in Figs. 1, 2 and 3, at the rear or inner side of the adjacent standard 1. The vertical portion 6 of each step or rung is provided with a cutout portion to provide an opening 9, through which projects one of the tongues 4, and the upper wall of the opening 9 is provided with a recess 10, which receives the horizontal portion of the adjacent L-shaped tongue 4, as shown in Fig. 3. The slot 8 in the horizontal portion 7 of each step or rung 5 communicates with a recess 11 formed in the lower edge of the part of the adjacent vertical portion 6, and the said recess 11 receives the horizontal portion of another of the L-shaped tongues 4, as shown in Fig. 2. The tongues 4 effectively support the steps or rungs 5 on the standards 1. The horizontal portions 7 of the steps or rungs 5, illustrated in Figs. 1, 2 and 3, are provided, adjacent their outer ends with slots 12, so as to provide hand grips 13, which can be conveniently gripped by a person during the act of ascending or descending the ladder.

In Fig. 4 of the drawings, a modified form of step or rung is illustrated, and is shown consisting of an L-shaped member having a vertical portion 15 and a horizontal portion 16. The horizontal portion 16 is of a width considerably greater than the width of the vertical portion 15 and is provided, at points on opposite sides of the vertical portion 15, with openings or cutout portions 17 to provide hand grips 18. The horizontal portion 16 is also provided with

an opening 19 for the passage of the standard 1 with which the said step or rung is to be associated. The vertical portion 15 of the step or rung, illustrated in Fig. 4, is 5 provided with a cutout portion 20 for the passage of one of the L-shaped tongues 4, and the upper end of the cutout portion or opening 20 is restricted, as at 21, to provide a recess for the reception of the horizontal 10 portion of one of the L-shaped tongues when the step or rung is mounted on one of the sections. The lower end of the vertical portion 15 is also provided with a recess 22 for the accommodation of another of the L- 15 shaped tongues 4 when the step or rung is mounted on one of the sections 1. A pair of inclined brace arms 24 have connection, respectively, with the vertical sides of the vertical portion 15 of the step, illustrated in 20 Fig. 4, and with the horizontal portion 16 thereof, and serve to reinforce the points of connection between the vertical portion 15 and horizontal portion 16, and also to serve as additional hand grips for a person during the act of ascending or descending the ladder.

The step or rung illustrated in Fig. 5 is similar to those disclosed in Figs. 1, 2 and 3, having a recess 25 at the point of connection between the vertical and horizontal portions for the passage of the standard 1 to which the step stud is to be connected, and the vertical portion is provided with an opening which has its upper end communicating with a recess 27 for the reception of the horizontal portion of one of the L-shaped tongues 4, when the step is mounted on the standard, and the lower end of the vertical portion is provided with another recess 28 for the reception of another of the horizontal portions of one of the tongues 4, so as to admit of the step or rung being securely supported on the standard. The horizontal portion of the step, illustrated in 45 Fig. 5, has its upper surface corrugated, as shown at 29, so as to provide an anti-slipping surface for the foot of a person when the person is either ascending or descending the ladder.

50 While the ladder is shown, in Fig. 1, as being associated with a fence post, it is to be understood that the same can be mounted at the corner of a building, or it can be mounted on a telegraph pole, the mast of a ship, or similar standards. However, the

ladder is designed, particularly, to be associated with a fence post, so as to admit of a person scaling the fence without coming in contact with the panel of the fence.

As shown in Fig. 1, the post is provided, at the upper end thereof, with an extension 30, which provides a hand hold which can be gripped by a person upon reaching the top of the post.

It is evident that various changes might be resorted to in the construction, form and arrangement of the several parts without departing from the spirit and scope of the invention.

What I claim is:

1. A ladder of the class described comprising a pair of sections each consisting of a standard having a series of tongues stamped therefrom, and a plurality of steps of L-shape in configuration and having horizontal portions provided with slots for the passage of the standards, and having the vertical portions provided with recesses for the reception of the tongues on the standards. 80

2. A ladder comprising a pair of standards, a plurality of steps associated with each of the standards and including a horizontal portion having a slot therein for the passage of the adjacent standard and a vertical portion having detachable connection with the standard, and hand grips formed on the horizontal portions of the steps. 85

3. A ladder including a standard, a plurality of steps associated with the standard and each consisting of a vertical portion for detachable connection with the standard, and a horizontal portion having a corrugated surface thereon, and provided with hand grips for the purpose specified. 90

4. A ladder including a standard, a plurality of steps associated with the standard and each consisting of a vertical portion and a horizontal portion carried by the vertical portion, inclined bracing elements having connection, respectively, with the vertical portion and the horizontal portion, and hand grips formed on the horizontal portion. 100

In testimony whereof I affix my signature in presence of two witnesses.

ZERAH G. HAYDEN.
